ELECTRODE HOLDER

Alex Strackbein, Edward S. Heck, and Arthur A. Henn, Milwaukee, Wis., assignors to A. O. Smith Corporation, Milwaukee, Wis., a corporation of New York

Application July 21, 1951, Serial No. 237,866

5 Claims. (Cl. 219—8)

1

The present invention relates to a holder for electrodes particularly as used in connection with electric arc welding.

An object of the present invention is to provide a lightweight well-balanced electrode holder to facilitate maneuvering of the holder in welding operations and minimize fatigue of the welder.

Another object of the invention is to provide an electrode holder having the live metal parts insulated to protect the operator and so that the holder may be set down in any position without danger of creating a short circuit.

Still another object is to provide a rugged electrode holder having a positively locking electrode grip and a simple effective means of securing a welding cable within the holder.

A further object is to provide an electrode holder wherein the electrical conductor is of a hollow nature to permit air to pass therethrough and thereby cool the holder during welding operation.

Another object is to provide an electrode holder which permits the electrode to be burned down close to the holder, to an extremely short length, without danger of shorting the electric arc.

The present invention is directed to an electrode holder having a generally hollow conductor. A welding cable is secured within the rearward end of the conductor and the forward threaded end of the conductor is engaged by a hollow insulating cap. A metal plug is disposed within the hollow cap and the welding electrode is received within a transverse opening in the cap and is firmly clamped between the metal plug and the forward end of the conductor as the cap is advanced on the threaded portion of the conductor.

An insulating sleeve or handle is disposed around the rearward unthreaded portion of the conductor and covers the weld cable connection.

Other objects and advantages of the present invention will appear in the course of the following description.

In the drawings:

Figure 1 is a longitudinal sectional view of the electrode holder of the present invention with parts in elevation;

Fig. 2 is a sectional view of the insulating cap;

Fig. 3 is a section taken on line 3—3 of Figure 1; and

Fig. 4 is a section taken on line 4—4 of Figure 1.

As shown in the drawings, the electrode holder of the present invention comprises a generally hollow, short, compact conductor 1 which is con-

2

structed of a metal having high electrical conductive properties, such as copper or a copper-base alloy.

A cylindrical terminal plug 2 is partially inserted within the open rearward end of the hollow conductor and secured therein by fillet weld 3. Terminal plug 2 is formed with a pair of non-communicating axial recesses, comprising the forward recess 4 which registers with the hollow interior of conductor 1, and the rearward recess 5 which receives the uninsulated forward end of the welding cable 6. By crimping plug 2 inwardly against the contained cable 6, as indicated by 7 in Figure 1, the cable is firmly secured to the terminal plug 2 and a simple, yet effective, electrical contact is thereby attained.

An insulating sleeve 8, which serves as a handle or grip, is disposed around the rearward portion of conductor 1 and covers the attachment of cable 6 to terminal plug 2. Sleeve 8 is secured to the conductor by a plurality of radially extending, countersunk set screws 9.

To cool the conducting elements 2 and 6 disposed within sleeve 8 so that the sleeve will be maintained at a comfortable temperature to the operator, the sleeve is radially spaced from the terminal plug 2 and is provided with a plurality of lateral cooling vents 10. Air or a similar cooling medium may circulate freely within sleeve 8 around terminal plug 2 and the attached welding cable 6.

Sleeve 8 by extending rearwardly beyond the point of attachment of cable 6 to terminal plug 2, prevents the cable from being bent excessively at the point of attachment as the electrode holder is maneuvered during operation, thereby reducing the tendency of the cable to become frayed or worn at this point.

To provide a firmer gripping surface for the welder and hence reduce operational fatigue, the rearward portion of sleeve 8 may be formed with a generally polygonal surface.

The forward portion of conductor 1 is provided with an exterior thread 11 and a tapered tip 12. The hollow interior of conductor 1 provides a passage 13 for the circulation of a cooling medium, such as air, and a plurality of circumferentially spaced vents 14 extend obliquely through the wall of the conductor at the base of tip 12 and communicate with the forward extremity of passage 13.

In addition, a plurality of circumferentially spaced ports 15 extend radially through sleeve 8, conductor 1 and terminal plug 2 and communicate with the recess 4 in terminal plug 2. As

hereinbefore stated, recess 4 registers with the passage 13 in conductor 1.

A hollow, interiorly threaded cap or head 16 engages the threaded portion 11 of conductor 1. Head 16 is generally cylindrical in shape and is constructed of a durable, light-weight insulating material.

The hollow interior of head 16 is provided with an internal annular groove 17 from which a plurality of transverse cooling ports 18 extend outwardly through the wall of head 16.

The vents 14 in conductor 1 register with groove 17 and a cooling medium such as air is free to circulate through ports 15, recess 4, passage 13, vents 14, annular groove 17 and ports 18.

A metal clamping block 19 is inserted within the hollow interior of head 16 and is secured at the forward extremity of the head by dowel pin 20 which extends through suitable aligned openings in head 16 and block 19.

The electrode 21 is received within a transverse opening 22 in head 16. Opening 22 intersects the hollow interior of head 16 and as the head is threaded onto the conductor the electrode is secured between the V-shaped notch 23 in clamping block 19 and the flat tip 12 of conductor 1.

Transverse opening 22 preferably does not extend completely through head 16, and the closed end of opening 22 serves as a stop to position electrode 21 within the head.

As the ends of dowel pin 20 are recessed from the outer surface of head 16 and as the metal block 19 is deeply embedded in the head, there are no metal parts adjacent the outer surface of head 16 wherein stray electric arcs may be set-up to short the electrical system. During welding operation, the portion of the head surrounding the opening 22, into which the electrode 21 is introduced, is apt to be charred or burned, and if the metal block 19 and dowel pin 20 were not deeply embedded in the insulating head, the block or the dowel pin might become exposed by this accidental burning of the head and thereby make the holder susceptible to short circuits. However, as the metal elements 19 and 20 in the present invention are a considerable distance from the outer surface of head 16, this danger is virtually eliminated and the electrodes can be burned to a considerably shorter length. As the electrode may be burned to a shorter length, fewer electrode replacements are necessary and a more efficient welding operation results.

As the head 16, which threadedly engages conductor 1, is constructed of insulating material, there is no danger of the engaged threads being burned or fused together if a short circuit should occur in the holder.

It is preferred that the external threads of conductor 1 and the cooperating internal threads of head 16 be left handed so that the head will tend to tighten on the conductor as a right handed welder intermittently taps or contacts the workpiece with the electrode to strike an arc.

The metal clamping block 19 is employed within head 16 to provide a firm, extremely durable electrode clamping surface, and if after prolonged service, the block should become worn, burned, or otherwise damaged, the block may be easily replaced by merely removing pin 20 and without the necessity of scrapping the entire head.

The present invention provides an electrode 75

holder designed to increase the efficiency of welding and minimize the fatigue of the welder. The conductor 1 being of a generally hollow nature, and the head 16 being constructed of insulating material result in a lightweight and well-balanced holder.

In addition, an effective cooling system is provided whereby air is circulated by convection within both the handle 8 and within the hollow conductor 1. This efficient cooling system prevents overheating or burning of the welder's hand and reduces operational fatigue.

Various embodiments of the invention may be employed within the scope of the accompanying claims.

I claim:

- 20 1. An electrode holder comprising a metallic conductor having a threaded portion at one end thereof, an insulating sleeve disposed about said conductor to provide a handle, means within said sleeve for securing a welding cable to the other end of said conductor, a hollow head of insulating material adapted to engage the threaded portion of said conductor, said head being formed with a transverse opening to receive a welding electrode, and a replaceable metallic clamping block disposed within said hollow head, said electrode being secured between said clamping block and the conductor as the head is advanced on the threaded portion of said conductor.
- 25 2. A lightweight electrode holder comprising, a metallic conductor having a threaded portion at one end thereof, tubular means secured to the other end of conductor for receiving a welding cable, said tubular means being crimped inwardly to secure said cable therein, a hollow head of insulating material adapted to engage the threaded portion of said conductor, said head being formed with a transverse opening to receive a welding electrode; a replaceable metallic clamping block disposed within said hollow head, said electrode being secured between said clamping block and the conductor as the head is advanced on the threaded portion of said conductor, and an insulating sleeve disposed about said conductor to provide a handle for the holder, said sleeve being open at one end and having vents for the passage of a cooling medium therein.

- 30 3. An electrode holder for electric arc welding comprising, a metallic conductor having a threaded portion at one end thereof, an insulating sleeve disposed about said conductor to provide a handle, means within said sleeve for securing a welding cable to the other end of said conductor, a hollow thick-walled insulating head adapted to engage the threaded portion of said conductor, said head being formed with a transverse opening to receive a welding electrode, a replaceable metallic clamping block disposed within said hollow head, and retaining means to removably secure said block within said head with said block and said retaining means being recessed from the outer surfaces of said head to prevent exposure of said block and said retaining means due to accidental burning of the head, said electrode being secured between said clamping block and the conductor as the head is advanced on the threaded portion of said conductor.
- 35 4. An electrode holder for electric arc welding comprising, a metallic conductor having a threaded portion at the forward end thereof and a hollow interior to conduct a cooling medium and having a plurality of cooling ports adjacent

the forward and rear ends communicating with the hollow interior of said conductor with the ports at the forward and extending generally longitudinally forwardly from the hollow interior of the conductor and flaring radially outwardly to effect cooling of the forward end portions of the conductor, a hollow insulating head adapted to engage the threaded portion of the conductor with the forward cooling ports in said conductor opening into the hollow interior of the engaged head, said head being formed with a transverse opening to receive a welding electrode and a plurality of cooling passages extending through the wall of said head and communicating with the hollow interior thereof to effect passage of cooling medium from one end of the conductor to the other, said electrode being secured between the head and the conductor as said head is advanced onto the threaded portion of said conductor, means for attaching a welding cable to the rearward end of said conductor, and an insulating sleeve disposed about the rearward end of said conductor to provide a handle for the electrode holder.

5. An electrode holder comprising a metallic conductor having a threaded portion at the forward end thereof and a hollow interior to conduct a cooling medium, said conductor being formed with a plurality of forward cooling ports in the wall thereof communicating with the forward portion of the hollow interior of said conductor and a plurality of rearward cooling ports in the wall thereof communicating with the rear-

ward portion of the hollow interior of said conductor, an insulating sleeve disposed around the rearward portion of said conductor to provide a handle, said sleeve being formed with a plurality of air vents which register with the rearward cooling ports in said conductor, a hollow insulating head adapted to engage the threaded forward portion of said conductor with the forward cooling ports in said conductor opening into the hollow interior of the engaged head, said head being formed with a transverse opening to receive a welding electrode and a plurality of cooling passages extending through the wall of said head and communicating with the hollow interior thereof, a metallic clamping block disposed within said hollow head, said electrode being secured between said clamping block and the conductor as the head is advanced on the threaded portion of said conductor, and means for attaching a welding cable to the rearward end of said conductor.
